UNITED STATES PATENT OFFICE

115,352

DESIGN FOR A CHAMBERMAID'S TRUCK

Eliot R. Scudder, Braintree, Mass., assignor to Jarvis & Jarvis, Inc., Palmer, Mass., a corporation of Massachusetts

Application January 24, 1939, Serial No. 82,553

Term of patent 14 years

To all whom it may concern:

Be it known that I, Eliot R. Scudder, a citizen of the United States, residing at Braintree, in the county of Norfolk and State of Massachusetts, have invented a new, original, and ornamental Design for a Chambermaid's Truck, of which the following is a specification, reference being had to the accompanying drawing, forming a part thereof.

The figure is a perspective view of a chambermaid's truck, embodying my new design.

I claim:

The ornamental design for a chambermaid's truck, as shown.

ELIOT R. SCUDDER.
